CLAIM

The ornamental design for a bat decoration with lights, as shown and described.

DESCRIPTION

FIG. 1 is a top perspective view of a bat decoration with lights design showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion "9" in FIG. 1; and,

FIG. 10 is an enlarged view of the selected portion "10" in FIG. 2.

The dash-dash broken lines illustrate portions of the bat decoration with lights. The dash-dot broken lines represent the bounds of the enlarged views. The broken lines form no part of the claimed design.

1 Claim, 10 Drawing Sheets
